UNITED STATES PATENT OFFICE.

GEORGE R. FLETCHER, OF CAMBRIDGE, OHIO.

TROLLEY.

No. 806,248.

Specification of Letters Patent.

Patented Dec. 5, 1905.

Application filed May 31, 1905. Serial No. 263,038.

To all whom it may concern:

Be it known that I, GEORGE R. FLETCHER, a citizen of the United States, residing at Cambridge, in the county of Guernsey and State of Ohio, have invented a new and useful Trolley, of which the following is a specification.

This invention relates to certain improvements in trolleys for electric-railway cars, and more particularly to novel means for removing ice and other obstructions from the trolley-wire, so as to insure a good electrical contact between the trolley-wheel and the overhead conductor.

15 The object of the invention is to provide a yieldably-supported scraper pivotally mounted on the axle of the trolley-wheel and adapted to engage the overhead conductor in advance of said wheel.

20 A further object of the invention is to provide a trolley-wheel having a lateral movement, whereby the same will readily follow the conductor in traveling around curves or in passing over switches.

25 A still further object is to provide a shield or guard for preventing the trolley-wire from catching under the trolley-supporting frame should the trolley-wheel accidentally jump the overhead conductor.

30 With these and other objects in view the invention consists in the construction and novel combination and arrangement of parts hereinafter fully described, illustrated in the accompanying drawings, and pointed out in the claims hereto appended, it being understood that various changes in form, proportions, and minor details of construction may be resorted to without departing from the principle or sacrificing any of the advantages 35 of this invention.

In the accompanying drawings, forming a part of this specification, Figure 1 is a side elevation of my improved device. Fig. 2 is a front elevation, partly in section. Fig. 3 is 45 a sectional top plan view of Fig. 1 with the trolley-wheel removed. Fig. 4 is a perspective view of the trolley-bracket detached. Fig. 5 is a similar view of the ice-scraper detached.

50 Similar numerals of reference indicate corresponding parts in all the figures of the drawings.

The numeral 5 designates the upper section of a trolley-pole one end of which is threaded, as indicated at 6, for detachable engagement with an adjacent section, while

its free end is provided with an angular extension 7, forming a base or support for the wheel-supporting harp or bracket 8. The harp or bracket 8, which is preferably stamped, cast, or forged from a single piece of metal, is provided with a pair of spaced arms 9, having perforations or openings 10 formed therein for the reception of the axle-bolt 11, upon which the trolley-wheel 12 is journaled, the base of said bracket being provided with a central opening 13, adapted to receive the attaching-bolt 14. The bolt 14 is loosely mounted in the opening 13, so as to permit free lateral movement of the bracket in passing around curves or over switches, said bracket being held in frictional engagement with the base of the angular extension by means of a coil-spring 15, interposed between the bottom of the extension, and an adjusting-nut 16, engaging the terminal threads of said bolt, as shown. The base or extension 7 is provided with a terminal segmental slot 17, adapted to receive a bolt or pin 18, secured to the bottom of the bracket or harp, whereby said bolt by engagement with the end walls of the slot will limit the lateral movement of the frame. It will thus be seen that by adjusting the nut 16 the tension of the coil-spring may be regulated at will to vary the pressure exerted by the supporting-bracket on the extension of the trolley-pole, while the frame is prevented from rotating on the head by means of the bolt or pin 18. The bracket 8 is also provided with longitudinally-disposed ears 19, one of which is formed with an opening 20 for the attachment of an operating-cord 21, while the opposite end is provided with a similar opening 22, adapted to receive a bolt 23 for retaining the ice-scraper 24 in position. 95 The scraper 24 is also preferably stamped from a single piece of metal and is provided with a pair of spaced arms 25, adapted to embrace the trolley-wheel, said arms being pivotally mounted on the axle-bolt and retained in position thereon by a nut 26, engaging the threaded end of said bolt. The free end of the scraper is bent upwardly at approximately right angles to the general plane of the body portion to form an angular extension 27, having a recess 28 formed in the end thereof for the reception of the overhead wire or conductor 29, said scraper being yieldably supported in contact with the conductor by a coil-spring 30, carried by the bolt 23 and interposed between said scraper and the adjacent longitudinal ear of the support. 105 110

ing-bracket. A nut 31 bears against the longitudinal ear of the bracket 8 for securing the bolt 23 in position, while a second nut 32 is threaded on the intermediate portion of 5 said bolt for regulating the tension of the coil-spring 30. Attention is here called to the fact that the bolt 11 serves as the journal for the trolley-wheel and also as the pivotal support for the scraper, the several parts being retained in position by a single clamping-nut 26.

As a means for preventing the trolley-wire from catching on the wheel-supporting frame, should the trolley-wheel accidentally 15 jump the overhead conductor, there is provided a guard or shield 33, one end of which is bolted or otherwise rigidly secured to the upper section of the trolley-pole, while its free end extends above the adjacent end of 20 the harp 8 and is provided with a terminal segmental recess 34 to permit free lateral movement of said frame.

The trolley-wheel may be provided with a lubricator-duct 35, through which oil may be 25 admitted to the journal, and, if desired, a washer 36 may be interposed between the supporting-bracket and the extension of the trolley-pole to prevent excessive wear on the latter.

30 From the foregoing description it is thought that the construction and operation of the device will be readily understood by those skilled in the art, and further description thereof is deemed unnecessary.

35 Having thus described the invention, what is claimed is—

1. The combination with a trolley-pole, of a harp secured to the pole and provided with a longitudinally-disposed ear, a trolley-40 wheel journaled in said harp, a scraper pivotally supported on the journal of the trolley-

ley-wheel, and a spring interposed between the scraper and ear for yieldably supporting the former in contact with the conductor.

2. The combination with a trolley-pole, of 45 a harp swiveled on the pole and having a trolley-wheel journaled therein, a scraper pivotally mounted on the journal of said wheel and yieldably supported in contact with the overhead conductor, and a guard or 50 shield secured to the trolley-pole and having its free end disposed between the harp and scraper.

3. The combination with a trolley-pole, of 55 a harp swiveled on the pole and provided with a longitudinal ear, a trolley-wheel journaled in said harp, a scraper pivotally supported on the journal of said wheel, a bolt connecting said ear and scraper, and a 60 spring carried by the bolt for yieldably supporting the scraper in contact with the overhead conductor.

4. The combination with a trolley-pole provided with an angular extension, of a 65 harp swiveled on the pole and provided with oppositely-disposed perforated ears, a trolley-wheel journaled in said harp, a scraper pivotally supported on the journal of the trolley-wheel, a threaded bolt secured to the scraper and engaging the perforation on the 70 adjacent ear of the harp, a spring carried by the bolt for yieldably supporting the scraper in contact with the overhead conductor, and a nut engaging the threads on the bolt for adjusting the tension of said spring. 75

In testimony that I claim the foregoing as my own I have hereto affixed my signature in the presence of two witnesses.

GEORGE R. FLETCHER.
